GUN BUTT PLATE

Calvin J. Albright, Jr., P.O. Box 695,
Bishop, Calif. 93514

Filed Oct. 26, 1970, Ser. No. 25,635

Term of patent 14 years

Int. Cl. D22—01

U.S. Cl. D22—7

FIG. 1 is an elevational view of the exterior or rear face of a gun butt plate embodying my new design.

FIG. 2 is a right side elevational view thereof.

FIG. 3 is an elevational view of the front or interior face thereof.

FIG. 4 is a top plan view taken from the plane indicated by line 4—4 of FIG. 1.

FIG. 5 is a bottom plan view taken from the plane indicated by line 5—5 of FIG. 1.

FIG. 6 is a cross sectional view taken in the plane indicated by line 6—6 of FIG. 1.

FIG. 7 is a cross sectional view taken in the plane indicated by line 7—7 of FIG. 1, and

FIG. 8 is a fragmentary sectional view taken in the plane indicated by line 8—8 of FIG. 3.

I claim:

The ornamental design for a gun butt plate, as shown.
